Harry W. Brown,
ATTORNEY.

UNITED STATES PATENT OFFICE.

NELLIE KEARNEY, OF HOLYOKE, MASSACHUSETTS.

DOLL.

1,425,974.

Specification of Letters Patent. Patented Aug. 15, 1922.

Application filed June 18, 1921. Serial No. 478,476.

To all whom it may concern:

Be it known that I, NELLIE KEARNEY, a citizen of the United States of America, residing at Holyoke, in the county of Hampden and Commonwealth of Massachusetts, have invented certain new and useful Improvements in Dolls, of which the following is a specification.

This invention relates to improvements in 10 dolls.

An object of the invention is to provide a doll structure, preferably of the kind known as rag dolls, wherein the opposite sides and faces of the doll are dressed or 15 made to represent different races, as will be fully described.

Heretofore it has been the custom to make or construct dolls so as to form the same with one or more faces, each having its body 20 differently clothed to correspond with the appearance of the face.

The present invention comprises the usual doll construction having the pivotally connected legs and arms, and the fixed body 25 and head portions; but with the additional features of a movable hat for hiding or covering one face and disclosing another, whereby by changing the position of the hat the appearance of the doll as a whole 30 may be changed. The pivoted legs are also adapted to be turned so as to correspond with the position of the exposed face.

Referring to the drawings:

Fig. 1 shows the doll with the hat in one 35 position, disclosing the face, arms, legs, and a suitable dress of a doll which represents a white person.

Fig. 2 is the reverse side of Fig. 1, showing the hat moved so as to cover the face 40 shown in Fig. 1, and disclosing suitable features to represent a colored person.

Fig. 3 is a side elevation of Fig. 2, illustrating the hat covering the white face and showing how each half of the body and arms 45 of the doll are covered to correspond with the face.

Fig. 4 is a detail view of the jointed structure for the legs, whereby the feet may be turned as shown in dotted and full line positions.

Referring to the drawings in detail: 1 represents the side of the doll that is white,

and 2 the side of the doll that is colored, both having the characteristic features painted, or otherwise placed on the material covering each half of the doll. The cap or hat is indicated at 3, and is provided with bows 4 and 5 on the opposite sides thereof which serve to pivotally secure the hat to the head portion at the points 6. The foot 60 portions 7 and 8 are pivotally connected at the knee portion, as indicated at 9, whereby the feet may be turned in opposite directions, as indicated in Fig. 4, depending on the position of the hat, so that the appearance of the doll may be uniform. These leg and feet members are suitably covered to represent stockings and shoes. The arms 10 of the doll may be pivotally connected to the shoulder part, as indicated by the dotted 70 line 11 in Fig. 1.

It is to be understood that the appearance of the doll as shown is not limited; as any suitable characters may be represented on the opposite sides and faces of the doll, 75 those shown being merely illustrative. The appearance of the dress as shown is also illustrative. If desired the entire dress may be of uniform appearance and color, or it may differ greatly in style and appearance 80 on both sides.

What I claim is:

1. As an article of manufacture, a doll having its opposite sides made different in appearance to represent different races, a 85 movable cap or the like attached to the head to cover either one of the faces, and leg portions, pivotally connected together whereby the feet and cap may be placed in corresponding relation to the rest of the article, 90 as desired.

2. As an article of manufacture, a doll having the body and head part formed as one piece, a dress for the body part, the head having its opposite sides decorated to represent different races, the appearance of the opposite sides of said dress corresponding in appearance with the opposite sides of said faces, a hat pivotally connected to the head and designed to cover either side of the 100 face, and legs pivotally connected to the body so as to be turned to correspond with the position of the hat, as described.

NELLIE KEARNEY.
